Primary Examiner — Sheryl Lane*Assistant Examiner* — Calvin E Vasant(74) *Attorney, Agent, or Firm* — Sughrue Mion, PLLC(57) **CLAIM**

The ornamental design for a dial, as shown and described.

DESCRIPTION

FIG. 1 is a top, front and side perspective view of a dial showing my new design;

FIG. 2 is a front elevational view thereof; and,

FIG. 3 is a rear elevational view thereof.

The broken lines depict portions of the dial and form no part of the claimed design.
